(57) **CLAIM**

The ornamental design for a resin building, as shown and described.

DESCRIPTION

FIG. 1 is a perspective view of a resin building showing my new design;

FIG. 2 is a front view thereof;

FIG. 3 is a right side view thereof;

FIG. 4 is a back view thereof;

FIG. 5 is a left side view thereof;

FIG. 6 is a top view thereof;

FIG. 7 is a perspective view of a second embodiment of a resin building showing my new design;

FIG. 8 is a front view thereof;

FIG. 9 is a right side view thereof, the left side view being a mirror image;

FIG. 10 is a top view thereof;

FIG. 11 is a perspective view of a third embodiment of a resin building showing my new design;

FIG. 12 is a front view thereof;

FIG. 13 is a right side view thereof;

FIG. 14 is a back view thereof;

FIG. 15 is a left side view thereof; and,

FIG. 16 is a top view thereof.

The phantom line representations in FIGS. 1-16 are exemplary and form no part of the invention.

1 Claim, 16 Drawing Sheets
